IRONING MACHINE

Wallace F. Oliver, Detroit, Mich., assignor to
Hydraulic Brake Company, Detroit, Mich., a
corporation of California

Application May 28, 1934, Serial No. 728,017

12 Claims. (Cl. 38—25)

This invention relates to ironing machines.

Broadly the invention comprehends an ironing machine including relatively movable ironing elements, one movable manually into operative position, means for locking this element in operative position, and the other movable by fluid pressure means to create an ironing pressure between the elements.

An object of the invention is to provide a machine for ironing or pressing textiles or garments including a power-actuated means capable of producing a relatively high pressure with a minimum effort on the part of the operator.

Another object of the invention is to provide an ironing machine including relatively movable ironing elements one of which is displaceable when the other element is moved into operative position so as to compensate for variations in the thickness of the work.

Another object of the invention is to provide an ironing machine including relatively movable ironing elements one of which is yieldingly supported by a column of fluid and maintained at a predetermined position with relation to the other element.

Another object of the invention is to provide an ironing machine including relatively movable ironing elements one of which is actuated by a fluid pressure means for creating an ironing pressure between the elements including means for yieldingly supporting the fluid actuated element upon a column of fluid under pressure and means for balancing the pressure on the column of fluid.

Another object of the invention is to provide an ironing machine including relatively movable ironing elements one manually movable into operative position and means for automatically locking this element in operative position, and the other actuated by fluid pressure means to create an ironing pressure between the elements, and manual means for actuating the fluid pressure means including means for unlocking the locking means, and means for returning the manually movable element to inoperative position.

Other objects and advantages of the invention will more fully appear from the following description taken in connection with the accompanying drawings forming a part of this specification, and in which,—

Figure 1 is a side elevation, partly in section, of an ironing machine embodying the invention;

Figure 2 is a sectional view substantially on line 2—2, Figure 1;

Figure 3 is a top plan view of the buck support;

Fig. 4 is a side elevation of the buck support mounted on the reservoir of the pressure producing unit;

Figure 5 is a sectional view of one of the fluid pressure operated motors, the buck, and guide means;

Figure 6 is a top plan view of the pressure producing device;

Figure 7 is an end view of the pressure producing device;

Figure 8 is a vertical sectional view substantially on line 8—8, Figure 6;

Figure 9 is a sectional view substantially on line 9—9, Figure 6;

Figure 10 is a sectional view substantially on line 10—10, Figure 6;

Figure 11 is a sectional view substantially on line 11—11, Figure 6;

Figure 12 is a diagrammatical illustration of the electrical heating and lighting circuit for the machine, and

Figure 13 is a diagrammatical illustration of the operating means for the ironing machine.

Referring to the drawings for more specific details of the invention, 10 represents a frame having a depression or pan 12 at one end and a hollow vertical column 14 at its other end. The column extends above and below the frame. The upper end of the column has a semi-spherical portion 16, the purpose of which will hereinafter appear, and the lower end of the column has a reduced portion 18.

A column 20 sleeved on the reduced portion 18 provides the main support for the frame, and legs 22 suitably secured to the frame cooperate with the column in supporting the frame. A top 24 supported on the frame has an opening receiving the column 14, a centrally disposed upwardly extending frusto-conical portion 26 open at its top as indicated at 28, and an apron 30 concealing the frame.

A pressure producing device 32 mounted in the pan 12 includes a reservoir 34 having a flange 36 on the wall thereof. A reciprocable piston 38 in the reservoir is retained against displacement by a washer 40 seated on a shoulder in the wall of the reservoir, and a transversely split ring 42 seated in a circumferential groove in the wall of the reservoir retains the washer against displacement. The piston 38 includes a concentric sleeve 44 having an extended portion provided with a

circumferential flange 46, and a leak-proof cup 48 on the head of the piston is held against displacement by the flange.

A hollow rod 50 has one of its ends threaded 5 in the sleeve 44, and its other end extends through the washer 40. A plug 52 is fitted in the outer end of the rod, and a spring 54 interposed between the piston and the washer 40 urges the piston toward the bottom of the reservoir. The rod has 10 a flat 56 for the reception of a tool for holding the piston in retracted position. Upon retracting the piston and removing the plug the reservoir may be filled through the rod.

A compression cylinder 58 and a valve chamber 60 are formed at the bottom of the reservoir in parallel relation to one another and normal to the reservoir. The compression cylinder has a low pressure chamber 62 and a high pressure chamber 64. The low pressure chamber has ports 15 20 66 and 68 communicating with the reservoir, and the high pressure chamber has a discharge port 70. A reciprocable piston 72 in the chambers 62 and 64 is retained against displacement by a transversely split ring 74 seated in a circumferential groove in the wall of the low pressure 25 chamber.

As shown, the piston 72 has heads 76 and 78 spaced apart by a sleeve 80. The head 76 is fitted in the chamber 62 and the head 78 is fitted in 30 the chamber 64. The piston has a skirt of reduced cross-section providing in conjunction with the wall of the cylinder 62 an annular chamber 82 communicating by way of the port 66 with the reservoir 34, and a leak-proof cup 84 is fitted 35 between circumferential flanges 86 on the skirt of the piston.

The head 76 of the piston has a plurality of 40 ports or passages 88 providing communications between the annular chamber 82 and that portion of the cylinder forward of the head 76. A collapsible leak-proof cup 90 loosely fitted in a circumferential groove in the wall of the piston checks the flow of fluid through the port 86 on the compression stroke of the piston. This cup 45 is normally held on its seat by a relatively light spring 92 interposed between the cup and an annular stop 94. A plug 96 threaded in the skirt of the piston provides in conjunction with the skirt a chamber 98 having a port 100 communicating with the annular chamber 82 and a plurality of ports 102 providing communications between the chamber 98 and that portion of the cylinder forward of the head 76.

The head 78 of the piston has a plurality of 55 ports 104 providing communications between the chambers 62 and 64, and a collapsible leak-proof cup 106 seated in a circumferential groove is adapted to check the flow of fluid through the ports 104 on the compression stroke of the piston, 60 and a spring 108 interposed between the cup 106 and the head of the cylinder serves to return the piston to its retracted position.

The sleeve 80 extends beyond the head 78, and is closed as by a plug 110 having a plurality of 65 ports 112 adapted to restrict the flow of fluid from the chamber 64 into the sleeve. A reciprocable piston 114 in the sleeve 80 has connected thereto a valve 116 urged by a spring 118 interposed between the valve and the plug 96 to seat on a washer 120 and to close the passages 102. Seated 70 on the head of the piston 114 is a leak-proof cup 122 held against displacement by an elongated nut 124 threaded on the rod of the piston.

The plug 96 threaded in the skirt of the piston 75 has a recess 126 receiving one end of a thrust rod

128, the other end of which is received by a cup 130 on an arm 132 keyed or otherwise secured to a shaft 134 journaled in a bearing 136 on the frame 10. An operating lever 138 is suitably secured to the shaft and an extension 140 adjustably attached to the operating lever has a hand grip or knob 142 secured to its free end. By applying force to the lever, the shaft may be moved through an angle and this movement is transmitted through the arm 132 and thrust rod 128 10 to the piston to move the piston on its compression stroke.

The valve chamber 60 has a port 144 providing a communication between the chamber and the reservoir 34, and a port 146 for return of fluid 15 from the system to the chamber. One end of the chamber is closed as by a plug 148 and a valve cage 150 is threaded in the other end of the chamber. The valve cage has a portion reduced in cross-section providing in conjunction with the 20 wall of the chamber an annular chamber 152 in direct communication with the port 144 and a plurality of ports 154 providing communication between the chamber 152 and the interior of the valve cage.

The head of the valve cage is fitted snugly in the chamber 60 and is provided with a concentric port 156. A leak-proof cup 158 is seated on the head of the valve cage and is held against displacement by a spring 160 interposed between the 30 cup and the plug 148. The cup has a concentric opening 162 of a smaller diameter than the port 156 so that the inner perimeter of the cup defining the opening 162 overhangs the port.

A reciprocable valve 164 in the cage has a 35 shoulder 166 normally abutting a shoulder in the cage and a concentric portion 168 adapted to enter the port 156 and to engage the overhanging portion of the cup to effectively seal the port. A hollow plug 170 threaded in the outer end 40 of the cage receives the stem 172 of the valve 164, and a washer 174 seated on the plug supports a leak-proof cup 176 having an opening receiving the stem of the valve. The stem of the valve is preferably made in two parts threaded together with a washer 178 interposed.

A compression spring 180 is sleeved on the stem of the valve between the washer and the head of the plug 170. By adjusting the plug 170 the tension on the spring may be regulated. 50 The head of the plug 170 has a plurality of notches 182 adapted to receive a spring-pressed stop 184 for locking the plug in adjusted position. The valve is actuated by a lever 186 secured to the shaft 134. As shown, the lever has 55 a bifurcated end straddling the stem of the valve and adapted to engage an adjustable stop 188 on the stem.

A buck support 190 mounted on the flanges on the reservoir includes an elongated receptacle 60 having its edges rolled to lend strength and rigidity to the structure. Cylinders 192 and 194 are mounted in the respective ends of the receptacle. The cylinders have formed thereon oppositely disposed guides 196 and 198, the purpose of which will hereinafter appear. These cylinders are connected respectively by conduits 200 and 202 to a coupling 204, and the coupling is connected by conduits 206 and 208 to the port 70 in the high pressure chamber 64 of the compression cylinder and to the port 146 of the valve chamber, respectively, and the conduit 206 has connected therein a check valve 210.

Reciprocable pistons 212 in the cylinders 192 and 194 have on their respective heads concentric 75

extension 214 provided with diametral passages communicating with axial passages through the pistons. Leak-proof cups 216 are seated on the heads of the pistons and are retained against displacement by the extensions 214, and bleeder screws 218 threaded in the axial ports in the pistons are enclosed by caps 220.

A buck 222 having upon its ironing face a pad 224 over which is spread a suitable cover 226 has on its back case-hardened inserts 228 in engagement with the caps 220, and sleeves 230 received by the guides 196 and 198 on the cylinders. The sleeves have therein rods 232 having heads 234, and compression springs 236 sleeved on the rods between the heads on the rods and retaining rings 238 fitted in circumferential grooves in the walls of the sleeves. The rods extend through openings in the bottom of the receptacle and have stops 240 threaded thereon.

An ironing head 242 adaptable for cooperation with the buck is pivotally connected to corresponding oppositely disposed horns 244 formed on a hollow arm 246 having a flared end 248 tele-scoping the semi-spherical portion 16 on the column 14 and an internal web 250 having a lateral arm 252,—which is in effect an extension of the arm 246,—pivoted to the semi-spherical portion and extending beyond the pivot 30 downwardly into the column 14. A rod 254 attached to the arm between the horns has a hand grip or knob 256 secured to its free end for lowering the head into operative position.

A bell crank lever 258 has its knee pivoted to 35 a bracket on the frame. One leg 260 of this lever is connected by a link 262 to the arm 252. The leg 260 and the link 262 provide a toggle limited in its movement by a stop 264. The other leg 266 of the bell crank lever is connected by a 40 spring 268 to the frame and by an adjustable rod 270 to an arm 272 loosely mounted on the shaft 134. The bell crank lever 258 has a cam surface 274 adaptable for engagement with a plunger 276 actuated by a cam 278 on the arm 45 132. This arm also has a driver 280 adapted to engage and actuate the arm 272. The arm 252 is raised to an elevated position by springs 282 connected between the arm 252 and the frame with an adjustable member 284 interposed for 50 regulating the tension on the springs.

A fluid pressure switch 286 is connected to the coupling 204. This switch is connected in a circuit 288 including a lamp 290 housed in the arm 246 back of an opening having therein a 55 colored glass 292. The circuit 288 is tapped off of a circuit 294 including a heating element 296 suitably arranged in the head 242 and a rheostat 298. The circuit 294 may be connected to any suitable source of electrical supply.

Assuming that the fluid pressure operating system is filled with suitable fluid, that the circuit 294 is connected to a suitable source of electrical supply, and that the head of the machine is in elevated position, under these conditions the buck 222 is yieldingly supported on two columns of fluid under pressure introduced in the reservoir 34 by the spring-actuated piston 38. This pressure is balanced by the springs 236 connected between the buck and the buck support 70 port to maintain the buck in a predetermined position to which position the buck is automatically returned at the end of each operation of the machine.

After placing the work on the buck, the head 75 242 is manually moved into operative position,

where it is automatically locked by the toggle connected between the arm 252 and the frame of the machine. If the article on which work is to be performed is thinner than the predetermined space between the buck and head, there will be no movement of the buck. However, if the article on which work is to be performed is relatively thick, the buck is proportionately displaced, resulting in movement of the piston 212 and displacement of fluid from the motors 192 and 194 back into the reservoir 34.

As the head 242 is moved into operative position, the extension 252 of the arm supporting the head is moved through an angle against the resistance of the springs 282. This movement of 15 the head aided by the spring 268 moves the toggle to over central position, and when the toggle assumes this position it is automatically locked against movement.

With the work upon the buck 222 and the head 20 242 lowered into operative position, the operator applies force to the hand grip 142 to depress the lever 138. This results in rotation of the shaft 134 through an angle and this movement of the shaft is transmitted through the arm 132 on the 25 shaft and thrust pin 128 to the piston 72 to move the piston on its compression stroke.

During the initial movement of the piston 72 on its compression stroke, the leak-proof cup 90 on the head 76 of the piston covers the port 30 68 and the fluid in the low pressure chamber 62 is displaced through the ports 104 in the head 78, past the leak-proof cup 106 into the high pressure chamber 64, thence through port 70, past valve 210, through conduit 206, coupling 204 and 35 conduits 200 and 202 into the motor cylinders 192 and 194, resulting in actuating the pistons 212 to move the buck 222 against the head 242. This movement of the buck is accomplished by the displacement of fluid due to initial movement of the piston 72 and further movement of the piston creates sufficient pressure to effectively iron the work.

This movement of the buck is against the 45 resistance of the springs 236 and results in compressing the springs between the retaining rings 238 in the sleeves 230 and the heads 234 on the rods 232. Upon obtaining a predetermined pressure in the system, the piston 114 is actuated by fluid under pressure in the high pressure chamber 50 64 to trip the valve 116 and thus render the head 76 ineffective for producing pressure, the fluid between the heads 76 and 78 being returned to the reservoir through ports 102, chamber 98, port 100, chamber 82 and passage 66, as the piston proceeds on its compression stroke. Because of the restricted flow of fluid from the chamber 64 into the sleeve 80, sudden movement of the piston 72 will not cause actuation of the valve 116. When the pressure between the ironing elements reaches 55 a predetermined degree, the fluid under pressure in the system actuates the switch 286 to close the circuit 288 and thereby light the lamp 290, thus giving a visual indication that the required pressure has been introduced between the ironing elements. Upon release of the applied force, the valve 210 closes to maintain pressure at the required degree.

After maintaining the pressure between the ironing elements for a sufficient period of time 70 to effectively iron the work, the operator raises the lever 140. This movement is transmitted to the shaft 134 and arm 132 carried thereby, whereupon the piston is returned to its normal retracted position under the influence of spring 108. 75

As the piston 72 returns to its retracted position, a vacuum is created in the cylinder 58 and the cups 90 and 106 collapse and fluid is drawn from the reservoir through the passage 66, the ports 5 88, past the cup 90, and thence through the ports 104, past the cup 106 to fill the chambers 62 and 64 for subsequent operation of the machine. When the piston 72 is fully returned to its retracted position the cup 90 uncovers the port 68 10 and any surplus fluid which may be drawn into the cylinder during the retraction stroke of the piston is returned through the port 68 to the reservoir.

Upon movement of the operating lever in reverse direction, the shaft 134 is rotated through an angle and this movement is transmitted to the arm 186, resulting in tripping the valve 164 and opening the port 156. Upon opening this port pressure is released in the motors 192 and 194, 20 resulting in movement of the buck to its normal position and return of fluid from the motor cylinders through conduits 200 and 202, coupling 204, conduit 208 to valve chamber 60, thence through port 154, chamber 152, and port 144 to the reservoir.

Further movement of the shaft in the same direction rocks the arm 132, causing the cam 278 thereon to travel beneath the spring-pressed plunger 276, and simultaneously therewith the 30 driver 280 on the arm 132 engages and actuates the lever 272. This movement of the lever 272 is transmitted through the rod 270 to the toggle to move the toggle past dead center, and upon movement of the toggle past dead center the 35 springs 282 function to automatically raise the head to the elevated position. When the head is in elevated position, the cam surface 274 engages the plunger 276 and locks the operating mechanism for the fluid pressure means.

40 Because of the initial pressure in the system, the buck 222 when in normal position is supported on two columns of fluid. It is highly desirable that the buck should be supported in a predetermined position so that the normal relation of the 45 buck to the head may be maintained constant when the head is in operative position. Hence, it is essential that means be provided for normally balancing the initial pressure in the system, and to that end springs 236 of a calculated tension are 50 connected between the buck and the buck support.

This invention has been described in connection with certain specific embodiments. The principles involved are susceptible of numerous other 55 applications that will readily occur to persons skilled in the art. The invention is, therefore, to be limited only as indicated by the scope of the appended claims.

I claim:

60 1. An ironing machine comprising relatively movable ironing elements, means supporting one of the elements for movement into and from operative position, means for locking this element in operative position, hydraulic means supporting the other element including a column of fluid displaceable upon movement of the first-mentioned element into operative position, means imposing an initial pressure on the fluid, means balancing the initial pressure on the fluid and 65 means for actuating the hydraulic means to create an ironing pressure between the elements.

2. An ironing machine comprising relatively movable ironing elements, means for supporting one of the elements for movement into and 70 from operative position, means for locking this

element in operative position, hydraulic means including displaceable columns of fluid for supporting the other element, means yieldingly retaining the fluid under pressure, means acting on the last mentioned element for balancing at 5 a predetermined pressure the pressure on the fluid, the column of fluid being displaced upon movement of the first-mentioned element into operative position, and means for actuating the hydraulic means to create an ironing pressure 10 between the elements.

3. An ironing machine comprising relatively movable ironing elements, means supporting one of the elements for movement into and from operative position, means for locking this element 15 in operative position, a hydraulic system for actuating the other element including a column of fluid for supporting the element in spaced relation to the first-mentioned element when moved into operative position, and means for actuating 20 the hydraulic means including means for closing the space between the elements upon initial movement of the hydraulic means to create an ironing pressure between the elements.

4. An ironing machine comprising cooperative 25 ironing elements including a head and a buck, means for supporting the head for movement into and from operative position, means for locking the head in operative position, hydraulic means for supporting the buck including a column of fluid, means for retaining the fluid under pressure, means acting on the buck for balancing at a predetermined pressure the pressure on the fluid to maintain the buck in a predetermined 30 position from which it may be displaced by 35 movement of the first-mentioned ironing element into operative position, said hydraulic means operable first to create an initial pressure between the buck and the head and then to create an ironing pressure between the elements. 40

5. An ironing machine comprising cooperative ironing elements including a head and a buck, hydraulic means for actuating the buck including fluid pressure actuated means operatively connected to the buck, a pressure producing device connected to the fluid pressure actuated means, a reservoir for supplying fluid to the device, means in the reservoir for maintaining an initial pressure on the fluid in the fluid pressure actuated means, and means for actuating the 50 device.

6. An ironing machine comprising cooperative ironing elements including a head and a buck, hydraulic means for actuating the buck including fluid pressure actuated means operatively connected to the buck, a pressure producing device connected to the fluid pressure actuated means including a cylinder, a piston reciprocable in the cylinder, a reservoir communicating with the cylinder, a spring-pressed plunger in the reservoir imposing an initial pressure on the fluid in the fluid pressure actuated means, and means for actuating the device. 55

7. An ironing machine comprising cooperative ironing elements including a head and a buck, hydraulic means for actuating the buck including fluid pressure actuated means operatively connected to the buck, a pressure producing device connected to the fluid pressure actuated means including a cylinder, a piston movable 60 therein for producing pressure, a reservoir communicating with the cylinder, a spring-pressed piston in the reservoir imposing an initial pressure on the fluid in the cylinder, means for balancing at a predetermined pressure the pressure 70 75

imposed by the spring-pressed piston to maintain the buck in a predetermined position, and means for actuating the device.

8. An ironing machine comprising cooperative ironing elements including a head and a buck, means supporting the head for movement into and from operative position, means for retaining the head in operative position, hydraulic means for actuating the buck including fluid pressure actuated means operatively connected to the buck, a pressure producing device connected to the fluid pressure actuated means including a cylinder, a piston movable therein for producing pressure, a reservoir communicating with the cylinder, a spring-pressed piston in the reservoir, and means acting on the buck for balancing at a predetermined pressure the pressure on the piston in the reservoir to maintain the buck in spaced relation to the head when the head is in operative position.

9. An ironing machine comprising cooperative ironing elements including a head and a buck, means for supporting the head for movement into and from operative position, means for locking the head in operative position, hydraulic means for actuating the buck including fluid pressure actuated means operatively connected to the buck, a pressure producing device connected to the fluid pressure actuated means including a cylinder, a piston movable therein capable of producing pressure, a reservoir communicating with the cylinder, a spring-pressed piston in the reservoir, means acting on the buck for balancing at a predetermined pressure the pressure on the piston in the reservoir to maintain the buck in a predetermined position, means for actuating the device first to impart an initial movement to the buck and then to create an ironing pressure between the head and the buck, and means for locking the actuating means when the ironing elements are in operative position.

10. An ironing machine comprising cooperative ironing elements including a head and a buck, means supporting the head for movement into and from operative position, a spring-actuated toggle for locking the head in operative position, hydraulic means for actuating the buck including fluid pressure actuated means operatively connected to the buck, a pressure producing device connected to the fluid pressure actuated means including a cylinder, a piston re-

ciprocable therein, means for retaining operating pressure, a reservoir for supplying fluid to the device, a spring-pressed piston in the reservoir, means acting on the buck for balancing at a predetermined pressure the pressure on the fluid, means for actuating the piston, and means for locking the actuating means when the head and the buck are in operative position.

11. An ironing machine comprising cooperative ironing elements including a head and a buck, means supporting the head for movement into and from operative position, a spring-actuated toggle for locking the head in operative position, means effective upon tripping the toggle to return the head to inoperative position, a hydraulic system for actuating the buck including fluid pressure actuated means operatively connected to the buck, a pressure producing device connected to the fluid pressure actuated means including a cylinder, a piston reciprocable therein for producing pressure, valves for maintaining operative pressure, a reservoir for supplying fluid to the device, a spring-pressed piston in the reservoir, means acting on the buck for balancing at a predetermined pressure the pressure on the fluid in the system, means for actuating the pistons, and means for locking the actuating means when the head and buck are in operative position.

12. In an ironing machine, a frame, a movable head and a movable buck mounted on the frame, means enabling the movement of the head to a position close to but out of contact with the buck, means for locking the head in this position, hydraulic means for forcing the buck against the head when the head is close to the buck comprising a fluid operated motor operatively connected to the buck, a pressure producing device connected to the motor for supplying fluid thereto and a reservoir connected to the device for supplying fluid to the device, means for controlling the flow of fluid between the motor and the reservoir, means for normally yieldingly maintaining the buck at a predetermined elevation with reference to the frame comprising means operative to exert pressure upon the fluid in the reservoir and thereby upon the fluid in the motor, and means acting on the buck to balance at a predetermined pressure the pressure on the fluid in the motor and reservoir.

WALLACE F. OLIVER.
